UNITED STATES PATENT OFFICE.

EDWARD B. CRAFT, OF HACKENSACK, NEW JERSEY, ASSIGNOR TO WESTERN ELECTRIC COMPANY, OF NEW YORK, N. Y., A CORPORATION OF ILLINOIS.

LIGHTNING-ARRESTER.

1,101,728.

Specification of Letters Patent. Patented June 30, 1914.

Application filed March 1, 1913. Serial No. 751,568.

To all whom it may concern:

Be it known that I, EDWARD B. CRAFT, a citizen of the United States, residing at Hackensack, in the county of Bergen and State of New Jersey, have invented certain new and useful Improvements in Lightning-Arresters, of which the following is a full, clear, concise, and exact description.

My invention relates to lightning arresters, and is particularly adapted for embodiment in arresters of the vacuum type.

The general object of my invention is to provide a new and improved arrester which is simple in construction, easy to manufacture, and reliable and efficient in operation. Although not limited to use in connection with telephone and telegraph circuits, it is particularly satisfactory in that service in which low cost of maintenance and reliability of operation are important factors.

My invention will be readily understood from the following description taken in connection with the accompanying drawing in which a lightning arrester embodying said invention is described and illustrated.

The drawing is an elevation of the arrester, the container, base and electrode structure being shown in cross-section.

The evacuated container 5, within which the electrodes of the arrester are mounted, may be of glass formed and evacuated in the same well-known manner as are incandescent lamp bulbs. The point 6 indicates the place at which the bulb or container is sealed after evacuation. Within the container 5 is an electrode support which has a hollow stem portion 7 resembling the well-known form of stem used in the filament support of an incandescent lamp, said stem having a flared bottom 8, the edges of which are welded at 9 to the edges of the container 5. Extending inwardly from the stem 7 is a solid or hollow rod 11, preferably of glass, upon which the electrodes of the arrester are supported. The stem 7 and rod 11 comprise the electrode support.

As shown in the drawing, the rod 11 is provided with a boss 12 upon which rests the inner cylindrical electrode 14 which is hollow and surrounds the rod 11. The outer electrode 15 is also cylindrical, and has a contracted portion 16, as shown in the drawing. Preferably both electrodes are made of aluminum, although they may be made of

copper, brass or other suitable metal. The outer cylindrical electrode 15 is held in proper relation to the inner electrode 14 by washers 18 and 19 of insulating material such as "lavite." These washers or disks 18 and 19 are perforated as shown at 20 in order to permit the ready evacuation of the space within the outer electrode 15, and to afford vents for the relief of any pressure created in said space by an excessive arc. The form of the washers 18 and 19 and the manner in which they coöperate with the electrodes 14 and 15 is apparent from the drawing, from which it is evident that the electrode structure can easily be assembled by placing the hollow cylindrical electrode 14 in position on the rod 11, then putting the washer 19 in place, then dropping on the outside electrode 15, then applying the washer 18, and finally by spinning over the end of the rod 11 as shown at 21. It is understood, of course, that such assembling is done before the electrode support is placed within the container 5.

Electrical connection with the electrodes 14 and 15 is obtained through leading-in wires 27 and 28 which pass through the top of the stem 7 and are sealed therein. The necessary air-tight seal may be obtained in the well-known manner by interposing pieces of platinum 25 in said leading-in wires within the glass seal. The inner ends of the leading-in wires 27 and 28 are connected to the electrodes 14 and 15 in any suitable manner as by welding or soldering or by the screws 30 as shown. The outer ends of said leading-in wires are connected to any suitable form of base which may be cemented to the outside of the container 5. The base shown in the drawing resembles an incandescent lamp base of well-known form, but instead of being threaded on its outer surface is provided with a projection 31 which is adapted to coöperate with a slot or groove in a supporting socket so as to provide a so-called "bayonet connection." The projection 31 is stamped up in the shell 32 which is of brass or other suitable material. At its bottom, said shell is spun in as shown at 33 and is embedded in molded insulating material 34, in which is also embedded a brass button 35 of the form shown. In manufacture, the base consisting of the shell 32, the molded material 34 and the but-

ton 35 is cemented to the end of the container 5 to which the electrode support has been welded. The leading-in wire 27 is brought out through a hole in the button 35 and is soldered to said button as shown at 36. The other leading-in wire 28 is brought out between the container 5 and the shell 32 and is soldered to the edge of the shell as shown at 37.

- 10 From the foregoing description, it will be apparent that the outer surface of the inner electrode 14 and the inner surface of the contracted portion 16 of the outer electrode can be so proportioned as to diameter that 15 a discharge through the arrester will take place at a given voltage; and that the electrodes can be easily assembled so that their coöperating arcing surfaces are in proper relation to one another. It will also be evident 20 that the arcing will be confined to the area between the contracted portion 16 of the outer electrode and the surface of the inner electrode 14, thereby keeping the arc away from the washers 18 and 19. This arrangement 25 of electrodes also effectively prevents the arc from reaching the walls of the evacuated container 5, which being preferably of glass would be damaged by such arc. The structure shown, therefore, permits repeated dis- 30 charges through the arrester without injury

to any parts adjacent the arcing surfaces of the electrodes.

I claim:

A lightning arrester comprising an evacuated glass container, a glass electrode support having a stem portion welded into and forming part of the wall of said container and having a rod portion extending from said stem portion into the container, a hollow cylindrical electrode surrounding and supported by the rod portion of said support, another hollow cylindrical electrode surrounding said first-mentioned electrode, insulating disks supporting said outer cylindrical electrode in operative relation to 45 said inner cylindrical electrode, leading-in wires sealed into and passing through said support and connected to said electrodes, and a base secured to the outside of said container and connected to said leading-in 50 wires whereby electrical connection may be made with said arrester.

In witness whereof, I hereunto subscribe my name this 26th day of February A. D., 1913.

EDWARD B. CRAFT.
